W. A. NAGEL.
PARACHUTE ATTACHMENT FOR AIRSHIPS.
APPLICATION FILED AUG. 13, 1912.
1,072,764. Patented Sept. 9, 1913.

UNITED STATES PATENT OFFICE.

WILLIAM A. NAGEL, OF HARRISON, OHIO.

PARACHUTE ATTACHMENT FOR AIRSHIPS.

1,072,764.

Specification of Letters Patent.

Patented Sept. 9, 1913.

Application filed August 13, 1912. Serial No. 714,931.

To all whom it may concern:

Be it known that I, WILLIAM A. NAGEL, citizen of the United States, residing at Harrison, in the county of Hamilton and State of Ohio, have invented certain new and useful Improvements in Parachute Attachments for Airships, of which the following is a specification.

The object of this invention is to provide a parachute which may be quickly released from an airship or aeroplane and which will be quickly opened to retard the descent of the aviator, so that, in the event of an accident, the aviator may reach the ground safely.

A further object of the invention is to provide means whereby the parachute may be stored within a small compass upon the air-craft and be positively released and opened when needed for use.

Other incidental objects of the invention will appear as the description of the same proceeds, and the invention consists in certain novel features which will be particularly pointed out in the claims following the description.

In the accompanying drawings which fully illustrate my invention: Figure 1 is a perspective view of a portion of an aeroplane showing the position of the parachute thereon when it is closed; Fig. 2 is an enlarged vertical section through the parachute container with the parachute therein; Fig. 3 is a perspective view showing the parachute released and partly open.

In carrying out my invention, I secure to a convenient point of the supporting frame, 1, of the aeroplane a preferably cylindrical holder or container 2 which is open at both top and bottom and is connected rigidly with the frame by brackets 3 at its lower end, as shown. The frame, or a part of the same, extends across the lower end of this container so as to form a stop for a coiled spring 4 therein, and the upper coil of the spring is engaged by hooks 5 formed on the upper end of keeper rods 6 depending from the container and having their lower ends provided with oppositely disposed lugs 7. These keeper rods are connected above their lower ends by a cross bar 8 carrying a pin 9 which may be engaged by one end of a lever 10 so that the rods may be drawn downwardly and thereby compress the spring. After the spring has been compressed, a horizontally movable locking rod or trip 11

is engaged over the lugs 7 so as to hold the keepers in their lowest position and retain the coiled spring in its compressed state. The lever 10 is fulcrumed upon a depending bail 12 or similar structure provided on the frame of the air-craft and may be removed after the spring has been compressed. The locking rod or trip 11 is pivotally mounted in the upper end of a short post 13 projecting from the said bail 12 between the lower ends of the retaining rods, as clearly shown.

The parachute 14, when it is folded and not in use, is fitted within a sectional tube or casing 15 which is adapted to fit within the container 2 and is provided with a top 16 having a depending flange which engages the upper ends of the sections of the tube so as to hold the same in their assembled relation. The rope 17 attached to and extending from the parachute is equipped with a bottom retaining plate 18 which engages the lower ends of the sections of the tube 15 so as to hold them together and permit them to readily enter the container 2. The rope or cable 17 is equipped at its free end with a belt 19 which is buckled around the waist of the aviator so that he will be prepared for instantaneous action in the event of an accident.

The parachute comprises a flexible textile cover and a folding frame consisting of ribs 20 and stretchers 21 pivoted to the ribs at their outer ends and at their inner ends pivoted to a disk or collar 22, a coiled spring 23 being connected with the said disk or head and with the upper ends of the ribs, as clearly shown in Fig. 2, and being normally under tension, so that, when the parachute is released, the spring will draw the head or disk 22 toward the upper ends of the ribs and thereby move the ribs outwardly at their lower ends and thereby open the parachute.

When the parachute is to be applied to the air-craft, it is folded so as to fit within the sectional tube 15, and the top 16 of said tube is then placed in position over the closed sections. The bottom 18 is then moved into engagement with the lower ends of the sections so that the tube will be held firmly closed around the parachute, after which it is inserted into the container 2 with the bottom 18 resting upon the spring 4 and the cable 17 extending upwardly between the tube and the container and projecting from the upper end of the container.

Should the use of the parachute be necessary, the aviator, by giving a quick lateral blow upon the retaining rod or trip 11, will release the same from the lugs 7, whereupon 5 the spring 4 will at once expand and eject the tube 15, with the parachute therein, through the upper end of the container. As the tube emerges from the container, the sections of the tube will tend to fall apart 10 under the pressure exerted thereon through the parachute by the spring 23, so that, when the lower end of the tube clears the container, the pull exerted upon the rope 17 by the weight of the aviator will withdraw 15 the bottom plate 18 from the tube and the sections of the same will fall away from the parachute which will then at once expand.

It will be readily noted that I have provided 20 a parachute which will open automatically and instantly without waiting for the influence of the air currents below the same as is the case with the parachutes in common use. It will also be noted that the 25 parachute is secured upon the frame of the air vessel in such a manner that it will be in position for instant use whenever needed, and, at the same time, will occupy very little space so as to offer practically no resistance to the passage of the vessel through 30 the air.

The coiled spring may be compressed by applying the hand directly to the cross bar 8 connecting the keepers 6, but the operation is made easier by using the lever 10, and 35 this lever may be removed after the spring has been compressed and the keepers engaged by the retaining rod or trip 11 so as to avoid any liability of the said lever interfering with the quick and automatic release of the parachute when it is needed.

If desired, a parachute of sufficient size 40 to support both the airship and occupant may be employed. If such is the case, the

rope 17 will be attached to the center of the top plane of the airship, thus causing the 45 latter to fall on an even keel, the planes therefore being level to resist the fall and practically support the weight of the airship.

Having thus described my invention, what 50 I claim as new is:—

1. The combination of a parachute, a sectional tube adapted to fit around the parachute when the same is closed, means within the parachute to open the same and separate 55 the sections of the tube, a container for said tube and parachute, and means for ejecting the tube and parachute from the container.

2. The combination of a container, a sectional tube adapted to fit therein, a parachute adapted to fold within said tube, means for ejecting the parachute and said tube from the container, means for normally holding the ejecting means inactive 60 retaining the parachute and the tube within 65 the container, means for releasing said retaining means whereby the parachute and the tube will be ejected, and means within the parachute to open the same and separate the sections of the tube.

3. The combination of a container, a sectional tube adapted to fit therein, a parachute adapted to fit within the sectional tube, a detachable top adapted to extend over the upper end of said tube, a bottom 70 plate connected with the parachute and adapted to engage the lower end of the collapsible tube, and means for ejecting said tube and the parachute from the container.

In testimony whereof I affix my signature 80 in presence of two witnesses.

WILLIAM A. NAGEL. [L. s.]
